UNITED STATES PATENT OFFICE.

J. WESLEY DODGE, OF MALDEN, ASSIGNOR OF ONE-HALF TO WILLIAM GORDON, OF BOSTON, MASSACHUSETTS.

MECHANICAL MOVEMENT.

SPECIFICATION forming part of Letters Patent No. 298,671, dated May 13, 1884.

Application filed March 7, 1884. (No model.)

To all whom it may concern:

Be it known that I, J. WESLEY DODGE, of Malden, in the county of Middlesex and State of Massachusetts, have invented certain Improvements in Mechanical Movements, of which the following is a specification.

This invention relates to means for operating reciprocating tools which are supported and reciprocated on stocks or supporting devices held and guided by the hand of the operator, as in certain classes of machines for burnishing parts of boot and shoe soles.

The invention has for its object to provide an improved mechanical movement whereby reciprocating hand-guided tools may be operated without causing the stock held by the operator to tremble or shake; and to this end the invention consists in a mechanical movement composed of a stock having a handle to be grasped by the operator and two curved segmental guides, two segmental slides adapted to reciprocate in said guides, and an arbor driven by suitable power and provided with eccentrics arranged to reciprocate said slides simultaneously in opposite directions, each slide being provided with a burnishing or other tool, while the stock is flexibly supported and connected with the motor, which rotates the above-mentioned arbor, so that the operator can move the stock and devices carried thereby in any desired direction, all of which I will now proceed to describe and claim.

Of the accompanying drawings, forming a part of this specification, Figure 1 represents a side elevation of my improved mechanical movement. Fig. 2 represents a front elevation of the same. Fig. 3 represents a side elevation showing the improved movement and means for supporting the same and rotating its arbor.

The same letters of reference indicate the same parts in all the figures.

In the drawings, *a* represents the stock supporting the burnishing-tools hereinafter described. The stock is composed of a handle portion or bar, *2*, adapted to be grasped by the operator, and an arched portion, *3*, con-

taining segmental guides for slides *4* *4*, each of which is a segment of a circle having the same radius as the guide in which it moves. In the upper end of the stock *a* is journaled a transverse arbor, *d*, having a pulley, *e*, and two eccentrics or crank portions, *f* *f*, which are connected by rods or pitmen *g* *g* with the slides *4* *4*, and when the arbor *d* is rotated reciprocate said slides in curved paths, the eccentrics being so arranged that the slides move simultaneously in opposite directions, the movement of each neutralizing the jar caused by the movement of the other, so that the operator's hand experiences no tremor or jar in holding the stock. The lower ends of the slides *4* *4* are provided with tools *5* *5*, adapted to perform the work for which the machine is intended. In the present instance said tools are burnishing-irons formed to act on the bottom of the shank of a boot or shoe; but it is obvious that my invention is not confined to any particular form of tools, nor to tools for any particular class of work. The stock *a* is in the present instance suspended by a rod, *b*, from a frame, *c*, which is pivoted to swing vertically, and thus allow the stock to rise and fall, the rod *b* being pivoted to the frame *c*, so as to oscillate in a vertical plane, and thus allow the stock to move backward and forward. The frame *c* is pivoted on a driving-shaft, *p*, and is provided with a counterbalancing-weight at its rear end. The forward end of the frame *c* has an arbor, *q*, which serves as the pivot for the rod *b*, and has two pulleys, one of which is connected by a belt, *s*, with a pulley, *t*, on the driving-shaft, and the other by a belt, *u*, with the pulley *e* on the arbor of the stock *a*.

I claim—

1. The improved mechanical movement composed of the flexibly-supported stock *a*, adapted to be grasped by the operator's hand, and having two segmental guides, two segmental slides adapted to reciprocate in said guides, and provided with operating-tools, and mechanism for reciprocating said slides simultaneously in opposite directions, as set forth.
2. The combination of the stock having the

handle portion and the segmental guides, the segmental slides 4 4, adapted to reciprocate in said guides, and provided with tools, as 5 5, the arbor *e*, journaled in the stock, and provided with two oppositely-projecting eccentrics and rods, *g g*, connecting said eccentrics with the slides 4 4, as set forth.

In testimony whereof I have signed my name

to this specification, in the presence of two subscribing witnesses, this 4th day of March, 1884.

J. WESLEY DODGE.

Witnesses:

C. F. BROWN,
WILLIAM GORDON.
